UNITED STATES PATENT OFFICE.

FRANCIS A. ISAACSON, OF MADRID, IOWA.

DETACHABLE SHOE-HEEL.

1,110,264.

Specification of Letters Patent.

Patented Sept. 8, 1914.

Application filed October 13, 1913. Serial No. 795,169.

To all whom it may concern:

Be it known that I, FRANCIS A. ISAACSON, a citizen of the United States, residing at Madrid, in the county of Boone and State of Iowa, have invented a certain new and useful Detachable Shoe-Heel, of which the following is a specification.

The object of my invention is to provide a detachable shoe heel, preferably of plastic material such as rubber, of simple, durable and inexpensive construction.

A further object is to provide such a shoe heel with parts so constructed and arranged that the heel may be readily and easily attached to or detached from a shoe heel, and also so arranged that the wear on the detachable member will not cause any parts to project upwardly through the heel of the shoe to inconvenience the wearer.

Still a further object is to provide a detachable shoe heel made of yielding material and provided with simple means for securing it to the welt of a shoe quickly, firmly and securely.

My invention consists in certain details, in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of a shoe with my improved detachable heel installed thereon, the welt, a portion of the shoe heel and the detachable heel being partially shown in section. Fig. 2 shows a transverse, vertical, sectional view of a portion of the shoe with my detachable heel installed thereon, the view being taken on the line 2—2 of the view of the plate shown in Fig. 4. Fig. 3 shows a longitudinal, vertical, sectional view through a portion of the shoe and detachable heel, the view being taken on the line 3—3 of the plate, as shown in Fig. 4. Fig. 4 shows a top or plan view of the metal plate which is received within the plastic body of the detachable heel, and Fig. 5 shows a vertical, central, sectional view of one of the cylinders.

In the accompanying drawings, the reference numeral 10 indicates generally a shoe which is provided with the inner sole 11 and the outer sole 12 and the welt 13. The outer or lower portion of the heel of the shoe 10 is preferably removed for the application of my detachable heel.

My improved detachable heel comprises a body 14 made of yielding plastic material, such as rubber, in the form of a shoe heel and having vulcanized or molded in said body a thin metal plate 15, preferably having the form of a U arranged in a horizontal plane with its open end forward. Star shaped or other shaped openings 16 are cut from the plate 15 to reduce the weight of the metal in the body 14 and also to permit the plastic material to flow or work into said openings for firmly fixing the plate 15 in position in the body 14.

For further accomplishing this object, the plate 15 is preferably provided with a plurality of sharp upwardly turned lugs 17 which hold the plate 15 and the body 14 against lateral movement. The plate 15 is provided with a plurality of pairs of holes 18.

When the detachable heel is formed with the plate 15 therein, a plurality of curved metal rods B is placed in the body 14. Each rod B comprises an upwardly extending member 19 extended through one of the openings of one of the pairs of openings 18 and another upwardly extending member 20 extending through the other opening of the pair. The member 19 extends upwardly in the body 14 to a point almost to the upper surface of said body but slightly spaced apart from said upper surface, as shown in Fig. 3. The member 20 extends upwardly within and beyond the body 14 and is screw threaded.

The detachable heel, constructed as above, is preferably secured to the shoe in the following manner: I preferably drill a plurality of holes through the upper and lower soles and the welt of a shoe in positions which correspond to the positions of the members 20 of the detachable heel when it is installed in position for use.

Received in the openings just described are hollow internally screw threaded cylinders 21 having enlarged heads 22 at their upper ends. In the upper ends of the cylinders 21 are horizontal slots 23 to receive a screw driver. The lower ends of the openings extending through the cylinders 21 are somewhat flared to make it easier to start the member 20.

The detachable heel is installed by inserting the members 20 upwardly into the holes in the shoe and then inserting the cylinders in the upper ends of said holes and screwing

them downwardly until they receive the screw threaded ends of the members 20. The members 20 are preferably of such length that they do not in any case extend to the inside of the shoe. The enlarged heads or upper ends 22 of the cylinders 21 are perfectly smooth on their upper surfaces except for the openings therein, and the slots 23 so that said heads do not inconvenience the wearer of the shoe.

My improved detachable heel has a number of advantages, among which are its simplicity of construction and its strength. The use of the U-shaped plate 15 furnishes a strong reinforcement for the plastic body 14. On account of the construction of the plate 15 with the openings 16 and the lugs 17, the plate is firmly held in position within the body 14 and in connection with the rods B holds the plate 15 and the body 14 firmly in the proper position on the shoe. The curved rod B serves a quadruple purpose. It helps to hold the body B against lateral movement with relation to the plate 15; it serves as a fastening means and the member 19 also serves to engage the heel member 12 when the body 14 is compressed and to thereby prevent the member 20 and the cylinder 21 from being pressed upwardly into the shoe and the form of said curved rod B is such that the rod is held against rotation so that the cylinder 21 may be readily and easily secured to it.

Should the detachable heel wear until it is desirable to remove it, any one may remove it by applying a screw driver to the cylinders 21 and another heel may be quickly and easily placed in position. The holes for the cylinders 21 and members 20 are preferably drilled but may be formed with a nail or any sharp instrument so that anyone who desires may attach my improved heel to a shoe.

It will be understood that many changes may be made in the details of the construction of my device without departing from its essential features, and it is my intention to cover by this application any such changes which may be within the scope of the appended claims. It will be understood, for instance, that the form of the member 20 might be varied in a great many ways and

the principal objects of my device might still be secured.

I claim as my invention:

1. A detachable heel lift, comprising a body of elastic material, a plate therein, spaced from the top and bottom and sides thereof, provided with pairs of holes and curved screw threaded rods extended through said pairs of holes from below, one arm of each rod being designed to engage a shoe heel and the other being screw threaded and extended above said body.

2. A detachable heel lift, comprising a body of elastic material, a plate therein, a screw threaded device on said plate extending upwardly therefrom having a part serving as a spacing block, and a coacting screw-threaded device designed to be in a shoe heel for securing the detachable heel lift to a shoe.

3. A detachable heel, comprising a body of elastic material, a plate therein, spaced from the top and bottom and sides thereof and provided with pairs of holes, curved screw threaded rods extended through said pairs of holes from below, one arm of each rod extending upwardly almost to the upper surface of said body, and the other arm extending above the body, and detachable engaging means on the upper ends of the latter arms.

4. In a device of the class described, the combination of a shoe having a heel portion with a detachable heel lift, comprising a body of elastic material, a plate therein, spaced from the top and bottom and sides thereof and provided with pairs of holes, curved screw threaded rods extended through said pairs of holes from below, one arm of each rod being designed to engage a shoe heel and the other being screw threaded and extended above said body and a plurality of internally screw threaded cylinders embedded in said shoe heel and formed with flat enlarged heads having slots to receive a screw driver, said cylinders being received on said screw threaded ends.

Des Moines, Iowa, October 8, 1913.

FRANCIS A. ISAACSON.
